ELECTRICAL SWITCH OF THE FLUID FLOW
TYPE

Max Nippold, Berlin-Halensee, Germany, assignor to General Electric Company, a corporation of New York

Application June 18, 1937, Serial No. 148,996
In Germany June 24, 1936

1 Claim. (CL 200—152)

The present invention relates to electrical switches of the fluid flow type, and especially to switches of this type having a sealed envelope which consists almost exclusively of metal.

5 A particular object of the invention is to provide an improved switch of the fluid flow type. Another object of the invention is to simplify the construction of such switches. Still other objects and advantages of my invention will appear 10 from the following detailed specification or from an inspection of the accompanying drawings.

The invention consists in the new and novel switch structure, as hereinafter set forth and claimed.

15 The somewhat fragile nature of the glass envelopes of the mercury switches which are now in extensive use has led to the development of switches in which metal is substituted to a large extent for these envelopes. In each of these switches it is, of course, still necessary to retain sufficient glass to insulate the separate contacts of the switch. As heretofore developed this has resulted in a seal of comparatively large diameter. I have now discovered that by a novel structure of my invention these switches may be made 20 of substantially all metal, with only the use of a small glass bead as insulation. This facilitates the manufacture of these switches in very small sizes, as compared to prior switches, and also affords numerous other advantages.

25 The invention is illustrated by means of several examples in the accompanying drawings, in which

30 Figure 1 shows the simplest possible form of the new switch,

35 Figures 2 and 2a show the introduction of the electrode through a material with coefficient of expansion which approximately agrees with that of glass,

40 Figures 3 and 4 show these switches in closed and open circuit position, respectively,

45 Figure 5 shows a beaker shaped switch with welded cover,

Figure 6 shows a tube shaped switch with 50 welded cover,

Figure 7 shows a tube with constrictions ready to be cut apart to form switch bodies,

Figure 8 shows a switch whose inlead is inserted insulated through the constriction at one 55 end, while the other constriction is welded shut, and

Figure 9 shows a switch with an enclosed steel sphere which is adapted for magnetic operation.

According to the invention as shown in Figure 55 1, a projection *b* is provided in a closed metal

tube *a*. In this metal tube, which is made of a material which is not attacked by the liquid, e. g. steel where mercury is used as the switch liquid, there is placed the switch liquid *c*. As the switch liquid mercury, or, where desired, as where the 5 switch may encounter high ambient temperatures, potassium-sodium, gallium etc. is used. The metal tube *a* serves as one contact, while the other contact is introduced as an inlead wire *d* through a suitable insulating bead *e* of glass or 10 the like. So that the switch liquid will not be contaminated or oxidized, a vacuum is produced in the tube, or preferably the tube is filled with a protective gas, such as nitrogen, hydrogen, or 15 the like, at any desired pressure, up to several atmospheres. In general, however, normal atmospheric pressure is chosen. The evacuation hole *f* at the end of the tube is closed after this process, for instance by sealing in a pin *g* or affixing a sphere.

20 The current capacity of such a switch is determined by the thickness and resistance of the inlead *d*, the quantity of the liquid *c* and the contact resistance between the metal and the liquid. As this contact resistance, such as that 25 between iron and mercury, for instance, is extremely high, a coating of platinum is preferably provided on the end of the inlead *d* and on the tube *a* around the glass bead *e*. This coating is produced in any suitable manner, as by melting 30 it on or by chemical or electrochemical means.

35 The voltage which the switch is capable of handling is determined by the distance between the inlead *d* and the metal casing, i. e. by the size of the glass bead *e*. This voltage capacity is, of course, easily altered by varying this distance.

40 Besides this glass insert, according to the invention an insert of porcelain or mica can also be used, which is particularly suitable for the switching of high frequency currents.

45 In the foregoing it is assumed that the switch envelope *a* is made of a metal, such as a special iron alloy (e. g. fernico), which has practically the same coefficient of expansion as glass. These alloys, however, are relatively expensive, and hence the insertion of inleads according to the invention is preferably accomplished by means of a ring *h* of this alloy which is welded into an envelope of any metal which is suitable for use with the switch fluid, as shown in Figure 2. Or, 50 as is shown in Figure 2a, magnified, this ring *h* is sealed on by an external weld. The latter method of construction has the advantage that the beaded glass inlead *d* can be fused to the ring *h* and the platinum coating *i* applied thereto. 55

after which this complete assembly is welded into the switch tube as a stopper after the switch liquid has been introduced, the tube evacuated, and the protective gas introduced. A special closing by pin or sphere is thus made unnecessary.

5 Figures 3 and 4 show such a switch in the on and off positions.

10 While Figures 1 and 2 show the general idea of the invention, Figures 5 to 9 present further methods of construction contemplated thereby. Thus Figure 5 shows a beaker shaped structure in which the on and off positions are reached by turning the switch on its axis $k-k$. The switch itself consists of the beaker l and the welded disc 15 m , which can be made of metal or of insulating material, and the switch liquid c . The disc m is in some cases made of a special iron alloy or of steel to which glass can be directly fused, in which case, as in Figure 2, the ring-glass seal is welded on. If the glass seal is made directly on the disc 20 m without a ring, then a filling hole must be provided, which is sealed by a sphere n .

25 Figure 6 shows a construction similar to that of Figure 5, in which however the envelope l is more tube shaped. With such a switch the switching can be accomplished by turning as well as by tilting.

30 Where a very large number of these switches are desired it is convenient to provide a seamless steel tube o with constrictions p , as shown in Figure 7. This tube is then cut through at these constrictions and the protective gas, switch liquid, 35 inlead with glass seal, and finally the metal ring are inserted at one end as shown in Figure 8. The other constriction is then sealed directly or

by means of a sphere n or the like, with the aid of welding heat.

Figure 9 shows yet another form with bent tube o in which another steel sphere q is introduced. When the coil r which is placed about the middle of said tube is momentarily energized this sphere is attracted and rolls to the other end of said tube, whereupon the switch, which is freely movable on its bearings, is tilted to this side and the liquid closes the circuit. When the coil is momentarily energized again, the sphere is attracted back, the switch tips and the circuit is opened. In this way a simple, effective and cheap remote control switch is obtained.

10 While I have described my invention herein- 15 before by reference to particular embodiments thereof it is to be understood that it is not limited thereto, but that various omissions, substitutions and changes, within the scope of the appended claim, may be made therein without departing 20 from the spirit of the invention.

What I claim as new and desire to secure by Letters Patent of the United States, is:—

25 A fluid flow switch comprising a metal container containing a conducting fluid, said container being of a metal which is substantially unaffected by said fluid, an opening in said container within which is welded a ring of a different metal which likewise is unaffected by said liquid and which has a coefficient of expansion comparable with that of glass, a glass-beaded inlead fused into said ring, and a platinum coating on said inlead and on said ring, said liquid being sufficient to close an electrical circuit between the coated areas on said inlead and said ring. 30 35
MAX NIPPOLD.
